R. E. DANIELS.
MACHINE FOR SHEARING AND BENDING METAL.

No. 603,813

Patented May 10, 1898.

UNITED STATES PATENT OFFICE.

ROBERT ELLSWORTH DANIELS, OF YOUNGSTOWN, OHIO, ASSIGNOR OF ONE-HALF TO HOSEA HUFFSTOT, OF SAME PLACE.

MACHINE FOR SHEARING AND BENDING METAL.

SPECIFICATION forming part of Letters Patent No. 603,813, dated May 10, 1898.

Application filed July 26, 1897. Serial No. 645,878. (No model.)

To all whom it may concern:

Be it known that I, ROBERT ELLSWORTH DANIELS, a citizen of the United States, residing at Youngstown, in the county of Mahoning and State of Ohio, have invented 5 certain new and useful Improvements in Machines for Shearing and Bending Metal, of which the following is a specification, reference being had therein to the accompanying drawings.

My invention relates to machines for bending and shearing metal, and is designed by certain mechanical constructions and arrangements of its parts to automatically form 15 and cut ready for the market a peculiar form of metallic fabric commonly known as "corner-shield" and used in the construction of buildings to form the edge of reentrant corners and to receive the plastering and prevent 20 the breaking away of the same, all as now well known to the builders' art.

In fully describing my invention I will use the accompanying drawings to illustrate the details thereof, and in which—

25 Figure 1 is a front elevation of my machine as it appears to the eye. Fig. 2 is a plan view thereof with covering-plates removed. Fig. 3 is a transverse section thereof on the line 3 3. Fig. 4 is a vertical section upon the line 4 4. Fig. 5 is a vertical section upon the line 5 5. Fig. 6 is a section upon the line 6 6 of Fig. 5. Fig. 7 is a segregated perspective of the shearing and bending dies; and Figs. 30 8 and 9 show the metal strip as it enters and 35 leaves the machine, respectively.

In the several views the same numeral always indicates the same part.

1 is the table or bed of the machine, supported by the legs 2, having the structural 40 webs 3, having the bosses 4, containing the bearings 5, in which are journaled the rocking shafts 6, to which are keyed the bell-crank 45 cranks 7, comprising the trip-levers 8, reaching to the central portion of the machine, and the levers 9, ending in the ball-head 10.

Depending from the mid-portion of the table or bed 1 are the hangers 11, having bearings 12, in which is journaled the power-shaft 13, receiving power from some convenient 50 source, and keyed to which are the parallel

cams 14, each impinging the end of one of the trip-levers 8.

From the mid-portion of the bed 1 there projects forward or to the front the brackets 15 and 16. The bracket 15 has the vertical slot 17, in which is keyed the slidable boxing 18, in which is journaled the stud-shaft 19 of the horizontal feed-wheel 20. A coil-spring 21 projects the boxing 18 in its seat toward the bracket 16, in the bearing 22 of which is 55 journaled the stud-shaft 23 of the horizontal feed-wheel 24, impinged by the wheel 20. At the lower end of the shaft 23 is keyed a ratchet-wheel 25, engaged by the pawl 26, pivoted in the box 27, having flanges 28, slidably keyed in the rail-slots 29 under the bracket 16. Within the box 27 is a spring 30, adapted to press the pawl into engagement. Journaled to the wrist-pin 31 of the box 27 is a pitman 32, pivotally secured to the 60 slot 33 of the crank-arm 34, keyed to the rocking shaft 6.

Adjacent to the respective ends of the bed 1 are disposed slots 35, through which project the lugs 36 of the die-carriages 37, the said 65 lugs containing the sockets 38, in which engage the heads 10 of the lever 9, forming a universal joint. The carriage 37 is provided with the flanges 39, sliding back and forth in the ways 40, made by the guide-blocks 41, secured to the bed 1. In the channel 42 of the carriages 37 are secured the hammer-block 43 and the bevel-faced die 44 by the yoke 45, secured to the carriage. The die 44 extends to the mid portion of the machine, where it meets 75 a bevel former-block 46, secured in the box 47 by the yoke 48 and adapted to be adjusted by the screws 49. The dies 44 are so disposed by means of certain packings 50 within the box 47 and set-screws 51 that during the 80 stroke of the machine they will pass sufficiently near each other to shear the strip 52 of material fed thereto by the feed-rolls 20 and 24 at the point 53, while the further movement of the said dies will bend the metal down 85 upon the former-block 46 into the wings shown at 54.

Beneath the die 44 is a slot 55 in the bed 1 of the machine, forming a channel, in which reciprocates the projecting lug 56 of the 90 100

- clamping-bar 57 and which contains the coil-spring 58, controlling the same. The bar 57 is of such length and is so adapted to slide upon the bed of the machine that the hammer-block 43 will strike it at the proper point in the traverse of the die 44 and that the said bar 57 will clamp the portion 59 of the metallic strip against the vertical face of the former-block 43 to aid in the bending of the wing 54.
- 10 Extending below the table 1 are the lugs 60, with lateral studs 61, bearing stiff coil-springs 62, also guided by the lateral studs 63 of the lugs 36 of the carriages 37, by means of which spring the said carriages are returned ready for the succeeding movement of the lever 8. The spring 58 will operate the clamp-bar in a similar manner, thus releasing the metal strip 52 sufficiently to permit the feed of the feed-wheels 20 and 24 of such diameter that the 15 movement of the pawl, already indicated, will feed sufficient material to make room for a new cutting and forming.
- 15 Adjustment of the former-block 46 is made by the set-screws 49 and of the shearing movement by the set-screws 51. The set-screws 64 and 65 adjust the movement of the hammer 43 and the die 44, while a further adjustment of the feed movement is obtained by means of the setting of the slot 33.
- 20 Having fully described my invention and indicated its operation, the latter need only be briefly described, as follows: The metal strip 52, as shown in Fig. 8, is fed intermittently into the machine by the feed-wheels, each intermittent thrust being regulated according to the width of the completed work. The strip being in the machine, the dies 44 and the clamping-bars 57 pass each other and, 25 shearing the metal, form it into wings against the former-blocks 46. The reverse movement of these parts taking place a new section of the material is fed into position for the new stroke.
- 25 Having fully described my invention, what I desire to secure by my Letters Patent and to claim is—
1. In a machine for shearing and bending metal as described, the former-blocks, the dies and clamps, means for actuating the said dies and clamps intermittently, and means for feeding the material between the said dies and clamps and said former-blocks intermittently, substantially as and in the manner described.
- 50 2. In a machine for shearing and bending metal, the former-blocks and the dies and clamps arranged in diagonal pairs, means for actuating the said dies and clamps intermittently, and means for intermittently feeding the material between the said former-blocks

and the said dies and clamps, substantially as and in the manner described.

3. In a machine for bending and shearing metalstrips, former-blocks secured oppositely diagonal upon a table, the sliding carriages 65 mounted upon said table, means for reciprocating the said carriages, the dies and hammer-blocks secured to said carriages, the reciprocating clamping-bar actuated by the said hammer-block, the feed-wheels adapted to 70 feed the material between the dies and the former-blocks, combined with means for intermittently actuating the said feed-wheels, substantially as described.

4. In combination with a bed, the sliding 75 carriages mounted thereon, the dies and hammer-bars secured in said carriages, the reciprocating clamping-bar actuated by the said hammer-bar, the former-blocks secured to the table, the cranks journaled to a rocking shaft 80 and actuating the said carriages, the cams actuating the said bell-cranks, the feed-wheels, the ratchet of one of the said feed-wheels, the pawl engaging the said rack, the pitmen and crank-arm actuating the said pawl, the 85 said crank-arm being keyed to the before-mentioned rocking shaft and means for rotating the cams, all substantially as and for the purpose described.

5. In combination with the bed, the car- 90 riages, the dies and hammers thereof, the clamping-bars, the former-blocks, means for reciprocating the said carriages, means for adjusting the said dies, the hammer-bars and the former-blocks, and mechanism for feed- 95 ing the material to the said dies and former-blocks, substantially as and for the purpose described.

6. In combination with the bed, the car- 100 riages, the dies and hammers thereof, the clamping-bars, the former-blocks, means for reciprocating the said carriages, means for adjusting the said dies, the hammer-bars, and the former-blocks, and means for feeding the material comprising feed-wheels, a spring 105 impinging one of said wheels upon the other, the ratchet of the latter wheel, the pawl engaging the said ratchet, the box in which said pawl is pivoted and the spring of said box, the pitmen pivoted to the said box, and piv- 110 oted to a crank-arm, the said crank-arm, and means for intermittently actuating the same, substantially as and for the purpose described.

In testimony whereof I affix my signature in presence of two witnesses.

ROBERT ELLSWORTH DANIELS.
